ATTORNEY.

UNITED STATES PATENT OFFICE

110,134

DESIGN FOR A SLIPPER

Rubin Kaminsky, New York, N.Y.

Application May 4, 1938, Serial No. 76,967

Term of patent 3½ years

To all whom it may concern:

Be it known that I, Rubin Kaminsky, a citizen of the United States of America, residing in city of New York, county of New York, and State of New York, have invented a new, original, and ornamental Design for a Slipper, of which the following is a specification, reference being had to the accompanying drawing, forming part thereof.

Fig. 1 is a plan view of a slipper showing my new design.

Fig. 2 is a perspective view thereof.

I claim:

The ornamental design for a slipper, substantially as shown.

RUBIN KAMINSKY.
